UNITED STATES PATENT OFFICE.

PAUL RIGOT, JR., OF WHEELING, WEST VIRGINIA.

FILE FOR CANCELED CHECKS.

Application filed May 4, 1923. Serial No. 636,521.

To all whom it may concern:

Be it known that I, PAUL Rigot, Jr., a citizen of the United States of America, and resident of Wheeling, county of Ohio, 5 and State of West Virginia, have invented certain new and useful Improvements in Files for Canceled Checks, of which the following is a specification.

This invention relates to a file for canceled bank checks, and it has for its primary object to provide a holder or file in which canceled checks may be disposed or arranged in orderly stacked relation and which permits convenient and full inspection of any of the checks carried thereby without removal of such check therefrom and without risk of such check being misplaced in the file following such inspection.

A further object is to provide a file of 20 the character mentioned which may serve as a permanent file and container, thus obviating the necessity for employing transfer files.

In describing the invention in detail, reference is herein had to the accompanying drawings, in which—

Figure 1 is a perspective view of the invention;

Figure 2 is a similar view of the file removed from its case;

Figure 3 is an end elevation of the file, showing a check withdrawn in position for inspection; and—

Figure 4 is an enlarged detail section 35 showing the threaded thimble.

Referring to said drawings, 1 indicates a flat bottom to which are rigidly attached the lower edges of a single upright side wall 2 and a single upright end wall 3, there 40 being thus formed a rectangular box-like container or file having one side, one end and its top wholly open. The bottom 1 has such dimensions that numerous canceled checks 4 stacked in orderly arrangement 45 may be readily accommodated thereon. To secure said checks in place, an upright metal post 5 is mounted upon the bottom 1 at a point adjacent to the angle between said bottom and the end wall 3 and also adjacent to the open side of the file, said post being preferably removable, having its lower end threaded for seating in a threaded metal thimble 6 embedded in said bottom.

55 The checks, previously provided with a single perforation 7 adjacent to the lower

left-hand corner, are so stacked that the said perforations thereof are in alined relation, thus permitting the introduction therethrough of the post 5 for threading 60 into said thimble 6.

It is to be noted that the post 5 stands at a distance from the end wall 3 greater than that of the check perforations 7 from the adjacent ends of the checks 4, thus providing for spacing the ends of said checks a suitable distance away from said end wall. So disposed, any check to be inspected may be swung outward from the stack, rotating upon the post 5, to a position at right angles to the stack, exposing 70 to view substantially its entire face. Following inspection, such check may obviously be swung back to its original position in the stack.

75 The file described is adapted for introduction within and to be slidable from a rectangular permanent file case, herein designated generally by the numeral 8, having one end open. Said case may be wholly 80 closed except at its said one end, or it may be partially open at the side thereof which is adjacent to the side wall 2 of the file when introduced.

A hasp-like handle 10 is mounted upon 85 the outer face of the end wall 3 of the check file, whereby the latter may be grasped for moving it in and out of the case 8.

From the foregoing it will be manifest 90 that I provide a file which is extremely simple and inexpensive to construct, which provides for the permanent filing of checks in an orderly arrangement and in small space, and which, while preventing displacement of filed checks, affords convenient 95 and ready access to and inspection of such checks. It will further be obvious that various changes in construction may be resorted to without departing from the scope or spirit of the appended claims.

100 What is claimed is—

1. A file for canceled checks, comprising 105 a rectangular box-like container consisting of a bottom, a single upright side wall and a single upright end wall, said bottom having dimensions exceeding, but approximating, those of checks to be received thereon, and an upright check-retaining post carried by said bottom and adapted for receiving thereon a lower corner portion of checks 110 stacked upon said bottom, said post being located adjacent both to said end wall and

to that edge of the bottom which is opposite said side wall.

2. A file for canceled checks, comprising a rectangular box-like container consisting of a bottom, a single upright side wall and a single upright end wall, said bottom having dimensions exceeding, but approximating, those of checks to be received thereon, an upright check-retaining post carried by 10 said bottom and adapted for receiving thereon a lower corner portion of checks stacked upon said bottom, said post being

located adjacent both to said end wall and to that edge of the bottom which is opposite said side wall, and an open-ended case within which said file is slidable to and from enclosed position.

In testimony whereof, I affix my signature in presence of two subscribing witnesses.

PAUL RIGOT, JR.
